In Germany December 16, 1939

6 Claims. (Cl. 250—175)

The invention relates to electric discharge devices and in particular to discharge tubes having a plurality of electrodes as, for example secondary emission multipliers.

It is an object of the invention to provide a discharge tube having a high output current and small dimensions. A further object is to provide a new arrangement and fastening of a multiplicity of gridlike electrodes arranged parallel to one another in close proximity which can be easily cooled from the outside of the tube envelope.

According to the invention the tube is made by placing a plurality of electrodes each having a flat metal extension and a plurality of insulating members one upon the other in alternating succession. The whole structure is then heated so that the extensions and the insulating members are fused together and an air-tight seal is formed between them. The extensions together with the interposed insulating material form a part of the wall of the discharge device. This method is particularly suitable for making secondary emission multipliers having, for example, a photoelectric cathode and a plurality of secondary emissive grids arranged substantially parallel to one another. The extensions have preferably the form of rings separated from one another by glass rings.

A construction of this type has the advantage that the dimensions of the discharge tube can be made very small in spite of the large number of connections to the outside. The tube can operate with high currents because the electrodes are easily cooled from the outside by means of the extensions carrying the electrodes.

Other aspects of my invention will be apparent or will be specifically pointed out in the description forming a part of this specification, but I do not limit myself to the embodiment of the invention herein described, as various forms may be adopted within the scope of the claims.

Referring to the drawing:

Fig. 1 shows a longitudinal section through a discharge tube according to the invention on an enlarged scale; and

Fig. 2 is a view of a tube according to the invention.

The discharge device of Fig. 1 contains in a glass envelope 1 a translucent photoelectric cathode 2 connected to the outside by a wire 3. The tube is furthermore provided with a plurality of electrodes 4a, 4b, 4c and so on, having secondary emissive properties. The last secondary emissive electrode consists of a plate 4n having a number of openings 8 for introducing the activating sub-

stances into the space containing the electrodes. The output electrode is a grid 6 arranged in front of the plate 4n. The grid-like electrodes 4a, 4b, 4c are connected to metal extensions 5a, 5b, 5c having the form of rings. The rings are separated from one another by insulating rings 1a, 1b, 1c, consisting for example of glass. The extensions of the electrodes are preferably made of copper. The metal rings and the insulating rings are connected so that an air-tight seal is formed between them.

A discharge device of this type is produced according to the invention in the following manner: The metal rings carrying the electrodes and the insulating rings are piled one upon the other in alternating succession. The parts are kept in their proper position by a frame or a suitable tool by which they are pressed together. Then the parts are introduced in an electrical high-frequency field so that the metal parts are heated up by eddy currents until they become red hot. The glass rings are then melted or fused together with the metal rings so that an air-tight seal is produced. The upper and lower portions of the envelope may have the form of tubes during this procedure and will be closed afterwards by heating the glass tube. The portion containing the photoelectric cathode 2 may also be preformed so that it has its final form when the rings are fused together. In order to keep the proper distance between the metal pieces during the heating process, it is preferable to introduce rigid spacing pieces having a high melting point between the electrodes before the structure is heated so that the electrodes are kept in their proper place during the heating process. The spacing pieces are removed after the tube has been cooled down.

Instead of the materials copper and glass other suitable materials can be used, producing a vacuum seal.

Fig. 2 shows a photoelectric tube including a multiplier approximately in natural size. The tube has the advantage that the heat produced during the operation is effectively guided to the outside so that the secondary emissive grids having heatsensitive layers can lead high currents while at the same time the electrodes are kept at a temperature at which the layers are not destroyed. In order to increase the cooling effect the discharge tube can be placed in a cooling medium, for example in a stream of air, oil or liquid air. The metal extensions act as cooling ribs.

Another important advantage of a device of this type consists in the fact that a large number

of electrodes can be connected at the outside of the tube with conductors having different potentials without requiring a complicated presser foot. The different potentials can be directly applied to the extensions 5a, 5b, 5c by means of contacts or the like. Another method is to apply a material 9 having high ohmic resistance to the insulating material so that this part of the tube envelope itself acts as the potential divider.

The invention is not limited to the device shown in the drawing. The distances between the single metal rings may be smaller or wider as required by the particular purpose of the tube. The extensions need not be circular, but may also have rectangular or other suitable forms. The extensions may at the same time be used to produce a desired capacitance between the electrodes and in this case it may be preferable to make the distances between the extensions as small as possible.

The invention has been described in connection with a highly sensitive photoelectric tube. It can however also be applied to multipliers having a control electrode, to transmitting and amplifying tubes, stabilizers and other tubes having particularly small dimensions.

What I claim is:

1. Method of producing vacuum discharge tubes including the steps of conductively connecting a plurality of electrodes each with a flat metal extension, placing a plurality of insulating members between said extensions, arranging said extensions and insulating members as a portion of the tube envelope and fusing said parts together so that an air-tight seal is formed between said insulating members and said metal extensions.

2. Method of producing high-vacuum discharge tubes including the steps of conductively connecting a plurality of electrodes each with a flat metal extension, placing a plurality of insulating members between said extensions, arranging said extensions and insulating members as a portion of the tube envelope, and fusing

45 said parts together by heating said extensions by means of eddy currents.

3. A vacuum tube including a plurality of electrodes, a plurality of flat metal rings, electrical connections between said electrodes and said flat metal rings and a plurality of fusible insulating rings separating said metal rings, the peripheral parts of said metal rings extending beyond said insulating rings towards the outside of said tube, said metal rings and said insulating rings forming a portion of the air-tight tube envelope.

4. A vacuum tube including a plurality of substantially parallel grid electrodes, each connected with a flat copper ring, a plurality of glass rings 15 separating said copper rings, the outer rim of said copper rings extending beyond said glass rings, said glass rings and said copper rings forming a portion of the tubular wall of the vacuum tube, and a layer of semi-conductive material 20 on said insulating rings connecting said metal rings.

5. A high-vacuum photoelectric tube including a translucent photoelectric cathode on a transparent portion of the tube wall, a plurality 25 of secondary emissive grids, an output electrode and a plate-like electrode each connected to a metal ring, said metal rings being mounted parallel to one another in close proximity, and a plurality of glass rings separating said metal 30 rings, said metal rings and said glass rings forming a portion of said tube envelope.

6. A high-vacuum photoelectric tube including a translucent photoelectric cathode on a transparent portion of the tube wall, a plurality of secondary emissive grids, an output electrode and a plate-like electrode each connected to a metal ring, said metal rings being mounted parallel to one another in close proximity, a plurality of glass rings separating said metal rings, said metal 35 rings and said glass rings forming a portion of said tube envelope, and a layer of said semi-conducting material on the outside of said glass rings connecting said metal rings.
